UNITED STATES PATENT OFFICE.

CHARLES O. L. CARDELL, OF PEARL RIVER, NEW YORK, ASSIGNEE TO DEXTER FOLDER COMPANY, OF PEARL RIVER, NEW YORK, A CORPORATION OF NEW YORK.

SHEET-REGISTERING MECHANISM FOR FOLDING-MACHINES.

1,053,705.

Specification of Letters Patent. Patented Feb. 18, 1913.

Application filed May 25, 1911. Serial No. 629,438.

To all whom it may concern:

Be it known that I, CHARLES O. L. CARDELL, a citizen of the United States, and a resident of Pearl River, Rockland county, State of New York, have invented certain new and useful Improvements in Sheet-Registering Mechanism for Folding-Machines, of which the following is a specification.

10 The present invention relates to an improved construction of sheet registering mechanism for paper folding machines by which the sheets fed to the folding machine are simultaneously registered longitudinally and laterally, to insure the proper position of the sheet above the folding rollers, not only with regard to the line of first fold, but also with regard to the line of the next succeeding transverse fold. In accomplishing this object, I provide an end gage which is movable toward and away from the folding rollers and side gages which are movable inwardly and outwardly transversely of the folding machine, and means for simultaneously imparting registering motions to the end gage and side registering gages. I prefer to adjustably mount the end gage upon two or more reciprocating rods or bars and provide rack and gear operating mechanism 25 for said bars to intermittently move the end gage toward and away from the line of fold, I prefer to adjustably mount the side registering gages upon said end gage by means of brackets and transversely reciprocating rods and arrange operating mechanism therefor in the form of rock shafts geared to the operating shaft of the end gage and having rock arms which engage the reciprocating supporting rods of the side gages to 30 impart the lateral registering motion to them. The operating shaft is actuated by a suitable cam mechanism to cause it to intermittently rock in its bearings to simultaneously impart the to and fro motions to 35 the end gage and side gages.

In order that my invention may be fully understood, I will first describe the same

with reference to the accompanying drawings and afterward point out the novelty more particularly in the annexed claims. 50

In said drawings: Figure 1 is a plan view of a part of a paper folding machine having my improved registering mechanism applied thereto. Fig. 2 is a side elevation of the same. Fig. 3 is an inside end elevation of 55 the same, and Fig. 4 is a detail vertical sectional view taken on the line 4—4 of Fig. 1.

In the drawings I have represented only sufficient parts of a paper folding machine to indicate the operation of my improved sheet registering mechanism. 1 represents the frame of the folding machine, 2 and 3 the first fold rollers geared together as indicated at 4. The folding knife is indicated at 5. 65

It is well understood in this art that sheets to be folded are passed into the machine by suitable conveyer tapes to carry the sheets into position above the folding rollers, the sheet being commonly arrested by a suitable front gage prior to its registration for the folding operation. The sheet is sometimes registered both longitudinally and laterally before it is acted upon by the first fold rollers and knife and in the present invention provision is made for simultaneously imparting this double registering motion to the sheet. 75

10 represents the end gage which arrests the longitudinal motion of the sheet into the folding machine and registers it longitudinally with relation to the folding rollers. This end gage 10 is preferably in the form of a heavy plate or bar extending transversely of the machine parallel with the folding rollers 2 and 3 and formed with internally threaded bosses 11 through which adjustably extend the threaded ends 12^a of the reciprocating supporting rods 12. These rods 12 are mounted in sleeves 13 so 80 as to move longitudinally with the sleeves and at the same time be free to rotate in the sleeves. Any suitable means may be provided for accomplishing this result, such, for 85

instance, as the set screws 14 threaded in the sleeves 13 and engaging the annular grooves 15 in the rods 12.

Mounted upon the rear end of each gage 5 supporting rod 12 is a worm gear 16 having a key screw 17 threaded through its hub and engaging the longitudinal spline groove 18 of the rod 12. This arrangement permits the worm gear 16 to rotate rod 12 and at the same time allows rod 12 to move longitudinally through the gear 16, for the purpose hereinafter made clear.

An adjusting shaft 20 extends transversely of the machine and is journaled in 15 the forked brackets 21 adjacent to its ends. This shaft 20 carries between the journals of said brackets 21 the worm gears 22 which constantly mesh with the worm gear 16 above referred to. One end of shaft 20 carries 20 a hand crank 24. By rotating the shaft 20 the rods 12 may be simultaneously rotated to adjust the end gage 10 toward and away from the folding rollers 2 and 3. Each of the sleeves 13 above referred to is freely 25 mounted in a bracket bearing 25 secured to the frame of the folding machine, and the upper face of each sleeve 13 has formed in it rack teeth 26 which mesh with a gear wheel 27 keyed to a transverse shaft 28 journaled 30 in suitable bracket bearings 29 projecting up from the bearings 25. The shaft 28 has secured to one end a rock arm 30 connected by a link 31 with a lever 32 journaled at 33 upon the machine frame and having 35 its lower short arm 34 provided with an anti-friction roller 35 operating in engagement with a face cam 36 secured to a shaft 37 journaled in suitable brackets mounted upon the machine frame and driven in any suitable 40 manner (not shown). A rod 38 is pivoted at 39 to the arm 34 and extends therefrom through a guide bracket 40 upon the machine frame.

41 is an expansion spring confined upon 45 the rod 38 between the guide 40 and a collar 42 adjustably secured to the rod. This spring actuated rod 38 holds the rock arm 32—34 in operative engagement with the cam 36.

50 The end gage member 10 carries a number of forwardly projecting bracket arms 50 in the forward ends of which are freely journaled the reciprocating rods 51, extending parallel with the gage 10, and separating in 55 the central longitudinal plane of the folding machine. Adjacent to the outer end of each of the rods 51 is adjustably mounted a side registering gage plate 55 which is presented at right angles to the end gage 10 above referred to. Each of these side gages 55 is 60 loosely mounted at 56 upon one of the rods 51, and is adjustably secured in the desired position by means of an arm 57 secured to rod 51 by set screw 58 and a threaded rod

59 secured to the rear face of gage plate 55 65 projecting through the arm 57 and engaged upon opposite sides of the arm by adjusting nuts 60 and 61. In this description it will be observed that each side gage 55 can be adjusted laterally of the folding machine 70 first by reason of the adjustable connection of arm 57 with rod 51, obtaining the general position of the gage, and second, by adjusting the screw nuts 60 and 61 upon the threaded rod 59. The construction and arrangement of both side gages 55 are the 75 same.

65 and 66 are auxiliary shafts extending at right angles to the operating shaft 28 and journaled in bracket bearings 67 and 68. 80 The bracket bearings 67 are supported from the shaft 28 as shown particularly in Fig. 1 of the drawings. Miter gears 70 keyed to the shaft 28, mesh with similar gears 71 keyed to the rear ends of auxiliary shafts 85 65 and 66 for causing said auxiliary shafts to rock to and fro simultaneously with the operating shaft 28. The forward portions of auxiliary shafts 65 and 66 are longitudinally splined as shown at 75. 90

80 is a rock arm depending from each of the auxiliary shafts 65 and 66 and keyed thereto so as to rock with the shafts but at the same time permit them to move longitudinally of the shafts when the registering 95 gages are adjusted. This keying of the rock arms to said auxiliary shafts is preferably accomplished by means of a key screw 81 passing through the hub of each rock arm 80 into the splined groove 75 of each shaft. 100 A plate 85, secured to each bracket bearing 68 as indicated at 86, is formed with a downwardly presented bifurcated flange 87 which straddles the shaft 65 or 66 and engages the hub of rock arm 80 for causing the rock 105 arm to move longitudinally of its shaft 65 or 66 when the end gage 10 is adjusted longitudinally of the machine.

Each rock arm 80 is formed with a bifurcated lower end as shown at 80^a which engages a pin 90 projecting laterally from the block 91 adjustably secured to one of the rods 51. By this means it will be observed that the rocking of shafts 65 and 66 through the mechanism described will cause arms 80 110 to reciprocate rods 51 in their bearings and move the side gages inwardly and outwardly 115 transversely of the machine.

The operation of my improved registering mechanism will be clear from the following 120 explanation: The registering position of end gage 10 longitudinally of the folder is determined by the hand adjustment of shaft 20 which rotates rods 12 in their supporting sleeves to move the end gage 10 toward or 125 away from the folding rollers. Since the side registering gages are supported by the end gage 10, it will be clear that they will

move longitudinally of the machine with said end gage so that their position adjacent to the ends of the gage 10 will always remain the same. To regulate the gaging position of the side gages 55, said gage plates are adjusted laterally of the machine by their adjustable supporting devices. Either one of the side gages may be used alone by moving the other out of active position, or 10 both side gages may be used at the same time. When the end and side gages have been adjusted to the desired positions, the machine is started with the result that each sheet passing into the machine will be arrested 15 by the end gage 10 and immediately after the arrest of the sheet, said gage 10 will move toward the folding rollers and simultaneously with this movement, one or both of the side gages will be moved inwardly, for imparting a double registering movement to the sheet. Immediately after the registry of the sheet, the gages move away from the sheet and the folding action takes place. In the movement of the end 20 gage toward and away from the folding rollers, it will be understood that the cam mechanism rocks the operating shaft 28 which through gears 27, racks 26 and sleeves 13, causes the supporting rods 12 and gage 10 to move longitudinally of the machine. The movement of the side gages is accomplished by rocking of shafts 65 and 66 and 25 their rock arms 80 acting upon rods 51 upon which gages 55 are mounted.

35 What I claim is:

1. In a mechanism of the character described, the combination of a gage member, supporting rods having threaded connection with said gage member, means for rotating said rods to adjust said gage member thereon, reciprocating sleeves in which said supporting rods are mounted, rack teeth upon said sleeves, a rock shaft extending transversely of said sleeves, gears 40 mounted upon said rock shaft and meshing with said rack teeth, and means for operating said rock shaft.

2. In a mechanism of the character described, the combination of a gage member, rods adjustably supporting said gage member, sleeves in which said rods are journaled, means confining said rods against longitudinal movement in said sleeves and permitting rotary movement of said rods in 55 said sleeves, gears splined upon said rods, an adjusting shaft extending transversely of said rods and carrying gears meshing with said rod gears, a rock shaft having rack and gear connection with said sleeves, and 60 means for operating said rock shaft.

3. In a mechanism of the character described, the combination of an end gage movable longitudinally of the machine, a side gage 65

movable thereon transversely of the machine, and suitable operating mechanism for simultaneously moving said end and side gages.

4. In a registering mechanism, the combination of an end gage movable toward and away from registering position, and reciprocatory supports for said end gage, with a side gage movably mounted upon said end gage, and movable thereon at right angles to the movement of said end gage, and 75 means for simultaneously operating said end and side gages.

5. In a registering mechanism, the combination of an end gage, supports for said end gage, a rock shaft geared to said supports 80 for moving said end gage toward and away from registering position, a side gage movably mounted upon said end gage, and gearing between said rock shaft and said side gage for simultaneously operating said end 85 and side gages.

6. In a registering mechanism, the combination of an end gage, reciprocatory supports for said end gage, a rock shaft geared to said supports for moving said end gage 90 toward and away from registering position, a longitudinally movable rod or bar mounted upon said end gage, a side gage mounted upon said rod or bar, and gearing between said rock shaft and said rod or bar, 95 for simultaneously operating said end and side gages.

7. In a registering mechanism, the combination of an end gage, reciprocatory supports for said end gage, a main rock shaft 100 geared to said supports for moving said end gage toward and away from registering position, a transverse rod or bar movably mounted upon said end gage, a side gage 105 adjustably mounted upon said transverse rod or bar, and an auxiliary rock shaft geared to said main rock shaft and operating said transverse rod or bar for simultaneously actuating said end gage and said side gage.

8. In a registering mechanism, the combination of an end gage, reciprocatory supports upon which said end gage is mounted, a main rock shaft geared to said supports for moving said end gage longitudinally of the machine, a rod or bar 115 mounted upon said end gage and extending transversely of the machine, a side gage mounted upon said rod or bar, an auxiliary rock shaft geared to said main rock shaft, 120 and a rock arm keyed to said auxiliary rock shaft and engaging said rod or bar, whereby said side gage will be moved transversely of the machine simultaneously with the movement of the end gage longitudinally of the machine.

9. In a registering mechanism, the combination of an end gage, reciprocatory sup-

ports upon which said end gage is mounted, a main rock shaft geared to said supports for moving said end gage longitudinally of the machine, a pair of rods or bars movably mounted upon said end gage and extending transversely of the machine, side gages adjustably mounted upon said rods or bars, auxiliary rock shafts geared to said main rock shaft, and rock arms

keyed to said auxiliary rock shafts and engaging said rods or bars, whereby said side gages will be moved transversely of the machine simultaneously with the movement of the end gage longitudinally of the machine.
